FASTENING INSERTING MACHINE

Benjamin B. Blanchard, Swampscott, Mass., assignor to United Shoe Machinery Corporation, Flemington, N.J., a corporation of New Jersey

Application March 8, 1941, Serial No. 382,413

22 Claims. (Cl. 1—20)

This invention relates to machines for inserting fastenings and, in some aspects, more particularly to means for fastening an upper to an insole before an outsole is applied to the shoe. The invention is herein illustrated as applied to a lasting machine of the type disclosed in United States Letters Patent No. 584,744, granted on June 15, 1897 upon an application of S. W. Ladd and R. F. McFeely, although it is to be understood that the invention is not limited to use in machines of that particular character.

It has been proposed to provide machines of the above-mentioned type with means for forming and driving fastenings, such as staples, to fasten shoe uppers to insoles in the manufacture of shoes of the through-and-through sewed type. The legs of the staples are clenched in the driving operation by engagement with a metal plate usually provided on the bottom face of each last upon which shoes of that type are made. In the use of such staples, one difficulty has been experienced in controlling the direction in which the ends of the staple legs are deflected with such a degree of accuracy as to avoid any interference between the staples and the outsole stitches whereby the outsoles are secured to the insoles. It has been found that if staples are used having the ends of their legs beveled in such a manner as to cause the legs of each staple to be deflected substantially in the plane of the crossbar of the staple, assurance is afforded against any such interference between the staples and the outsole stitches; and, in one aspect, the present invention aims to provide improved means for forming staples of that character.

In the illustrated machine, the staples are formed from pieces severed from a continuous length of fastening material, the severing means being arranged to sever the material at an oblique angle to its longitudinal axis. The feeding of the fastening material occurs before each severing operation, and in order that the bevels at the ends of each severed piece will be on the same side of the piece and, accordingly, in the desired relation on the ends of the legs of the staple when formed, there is provided, in accordance with a feature of the invention, novel means for turning the fastening material alternately in opposite directions 180° about its longitudinal axis between successive severing operations. Preferably, and as illustrated, the fastening material in each cycle of the machine is turned 90° about its longitudinal axis after it is fed but prior to the severing operation and thereafter is turned 55

reversely 90° to cause it to be presented in an untwisted condition each time it is fed, the direction of both turning movements being reversed in alternate cycles of operations of the machine.

In fastening the uppers of shoes to insoles by means of staples driven and clenched in the manner above described, it will be evident that the quality of the work will be improved if staples are used of such lengths as to insure that they will be properly clenched without any excessive length of fastening material in the clenched portions of the staples. Since the upper materials to be fastened are frequently of different thicknesses at different portions of the same shoe, it is desirable that the lengths of the staples be varied in accordance with such variations in thickness of the upper materials. Accordingly, the invention further provides novel means whereby the length of the fastening material fed and, consequently, the length of the staple formed may be conveniently and quickly varied in operating upon each shoe. As herein illustrated, there is provided a member movable to operate the fastening-feeding means and a stop for limiting the movement of this member to determine the length of fastening material fed to form a staple. Since machines of the type herein shown are each provided with a pair of relatively movable edge gages arranged for alternative use respectively to position the shoe in operating along different portions of the shoe bottom where fastenings of different lengths are required, in the construction herein shown the relative movement of the edge gages is utilized to control means for varying the position of the above-mentioned stop to vary the length of the fastening material fed. In the construction shown, this means comprises a rotary eccentric for varying the position of the stop, a device for rotating the eccentric by the relative movement of the edge gages, and adjustable stops for variably determining the different positions of this device corresponding to the desired lengths of fastenings for use in operating upon different portions of the shoe. Conveniently, the device for varying the position of the stop for determining the length of feeding movement of the fastening material is arranged also simultaneously to adjust the position of the severing means so as to cause the legs of each staple when formed to be of equal lengths.

The above and other features of the invention, including various novel details of construction and combinations of parts, will now be more particularly described with reference to the accompanying drawings and pointed out in the claims.

In the drawings,

Fig. 1 is a view in left-hand side elevation of a portion of the head of a machine in which novel features of the invention are embodied;

Fig. 2 is a view of a portion of the head of the machine in right-hand side elevation;

Fig. 3 is a view in front elevation of portions of the head of the machine;

Fig. 4 is a view in right-hand side elevation of the wire-cutting mechanism;

Fig. 5 is a detail view on an enlarged scale of a portion of the mechanism shown in Fig. 2;

Fig. 6 is a view in left-hand side elevation of a portion of the staple-forming mechanism and the shoe-positioning means;

Fig. 7 is an enlarged view in vertical section of the wire-guiding member and of a portion of the means for rotating it;

Fig. 8 is a detail view of the cam for operating the mechanism for rotating the wire-guiding member;

Fig. 9 is a view on an enlarged scale of a staple formed by this machine;

Fig. 10 is an enlarged view in front elevation of the wire-guiding, wire-cutting and staple-forming mechanisms of the machine;

Figs. 11 to 14 inclusive are diagrammatic views illustrating the different steps of turning and cutting the wire to form different severed pieces in successive cycles of operation of the machine; and

Fig. 15 is a perspective view of a portion of a completed shoe, the upper of which has been fastened to the insole by the use of the illustrated machine, and illustrating the relation of the staples to the outsole stitches.

Since the invention is illustrated as embodied in a machine of the type disclosed in the above-mentioned Letters Patent, only such features of its general organization as it is necessary to refer to, for an understanding of the invention will be disclosed herein in detail. It will be understood that machines of the illustrated type are generally used for lasting shoes along their opposite sides and sometimes also around the toe ends, each shoe on its last being supported in the hands of the operator and presented successively in different positions for the operation of the machine. To assist in determining the proper relation of the shoe to the lasting instrumentalities, the machine is provided with the usual shoe bottom rest 20 (Fig. 1) arranged to engage the outer face of the insole, and with two edge gages 22 and 28 arranged to be used alternatively in operating upon different portions of the shoe bottom. The thin edge gage 22 is secured to a bracket 24 fast on the head 26 of the machine and is arranged to engage the side of the shoe at or near the edge of the insole to guide it in lasting the opposite sides of the shank and ball portions, and the thick edge gage 28 (adapted for use) is used to support the shoe in lasting around the toe end and also at the opposite sides in locations at or just rearwardly of the heel breast line. The edge gage 28 in the illustrated machine is arranged to slide along a guiding rib 30 on the bracket 24 into and out of position for use in place of the edge gage 22 and is provided with a finger-piece 32 by means of which the operator may conveniently move it forwardly and rearwardly into and out of operative position. As shown particularly in Fig. 6, there is pivotally connected to the bracket 24 a spring-operated latch 33 which is arranged by engagement with a shoulder 35 on the gage member 28 to lock the gage member in its forward operative position. The finger-piece

32 is pivoted at 37 to the gage member 28 so that it may be swung relatively to the gage member to operate the latch 33 to release the gage member for movement to its rearward inoperative position. The machine is provided with gripper mechanism comprising a pair of cooperating jaws 34, to which the usual closing, updraw and overdraw movements are imparted by mechanism which is substantially the same as that shown in the above-mentioned Letters Patent. For wiping the margin of the upper inwardly over the insole, there is provided a wiper 36 carried by a slide 38 which is movable along a horizontal guideway in the head 26 of the machine and to which there is imparted one complete reciprocation in each cycle of operations of the machine to cause the wiper 36 to wipe the marginal portion of the upper inwardly over the outer face of the insole and to withdraw. A staple driver 40 is fastened to a driver bar 42 which, as more fully shown and described in the prior Letters Patent, is movable in a guideway formed in a carrier (not herein shown) journaled for swinging movement in trunnions formed in a bracket fast to the head 26. In the illustrated machine the slide 38 has adjustably secured thereto a block 44 which serves as an abutment (Figs. 2 and 6) and which is arranged to engage an abutment 46 on the driver bar 42 near the end of the forward movement of the slide 38 and to swing the driver bar 42 and the driver 40 with it, thus alining the driver with a staple-guiding passageway in the wiper 36 and maintaining such alinement during the remainder of the overwiping operation. The block 44 carries an adjustable screw 45 that engages a portion of the slide 38 and by means of which the block may be adjusted relatively to the slide, the block being then locked in adjusted position by means of a bolt 47 carried by the slide and extending through an elongated slot 49 in the block, a lock-nut 51 being provided for holding the screw 45 in adjusted position. It will be understood that the driver bar 42 is raised by a cam (not shown) against the resistance of a torsion spring and is released by the cam to the action of the spring for the staple-inserting operation after the completion of the forward movement of the wiper 36 and the slide 38.

In the illustrated construction, the staple-forming instrumentalities of the machine, comprising an outside former 48 and an insider former 50 (Figs. 2 and 6), are carried by the slide 38 on which is also mounted a portion of the mechanism for operating these parts to form a staple from a fed-in portion of wire. Conveniently the forward movement of the slide 38 is utilized to operate such mechanism, and in order that the slide 38 may receive a reciprocatory movement of sufficient extent for the purpose in view it is formed in two parts connected by a lever 52 (Fig. 2) which is fulcrumed at 54 to a bracket 56 secured to the head 26 of the machine by screws 55. As shown, the lever 52 at its upper free end is provided with a slot 58 in which there is slidably mounted a block 60 pivotally connected to the forward portion of the slide 38 and with a slot 62 located substantially midway between its ends in which there is mounted to slide a block 64 pivotally connected to the rear portion 66 of the slide 38 which is reciprocated once in each cycle of operations of the machine by the usual lever 68 and cam 70 fast on a cam shaft 72 journaled in suitable bearings in the head 26. As shown in Fig. 2, there is adjustably secured to the bracket 56 by one of

the screws 55 a bar 71 provided with an elongated slot 73 to receive the screw 55 and with an elongated slot 75 into which extends a pin 77 that projects from the bracket 56. At its forward end the bar 71 has a laterally extending portion 79 into engagement with which the driver bar 42 is moved by the block 44 at the end of the forward movement of the slide 38, the bar 71 thus assisting in maintaining the driver bar and driver 40 in alignment with the driver passage in the wiper 26 for the driving operation.

When the slide 38 is in its rearward position, wire for forming the staples is fed by means hereinafter described between the inside and outside formers of the machine, the wire being guided by a nozzle 74 (Figs. 3 and 10) which is fast to a bracket 76 adjustable transversely of the slide 38, by means hereinafter described, on a guideway 78 (Fig. 4) formed on a bracket 80 which is secured to the head 26 by screws 82. The wire is severed by a cutter 84 which is fast to a slide 86 movable in the bracket 76 in parallel relation to the slide 38. The cutter 84 cooperates with the wire-guiding nozzle 74 to cut the wire before the forming of the staple begins. The cutter 84 and the nozzle 74 have their co-operating faces inclined (as shown in Figs. 3 and 10) to sever the wire at an angle to its longitudinal axis. Pivotedly connected to the slide 86 is a pawl 88 (Fig. 4) provided with a tail portion 90, between which and a lug 92 on the slide 86 there extends a spring 94 which tends normally to hold the pawl in engagement with the lower face of a block 96 fast to the slide 38. Pivotedly connected to the bracket 76 is a bell-crank lever 98 provided with an upwardly and rearwardly extending arm carrying a roll 100 and with a downwardly extending arm 102 carrying an adjustable screw 104 held in adjusted position by means of a lock nut 106. A U-shaped spring 108 on the bracket 76 tends normally to swing the bell-crank lever 98 in the direction to press the adjustable screw 104 against the forward end of the cutter slide 86 and to move the slide 38 rearwardly. This movement of the cutter slide is limited by engagement of an adjustable screw 95 (Fig. 3) carried by the slide with a portion of the head 26, the screw 95 extending through a lateral projection or flange on the front end of the slide and engaging an adjacent portion of the head 26. It will be understood that by adjustment of the screw 95 the initial position of the cutter 84 relatively to the nozzle 74 may be varied. From the above description it will be evident that the cutter slide 86 is connected to move forwardly with the slide 38, thus causing the cutter 84 to sever the fed-in portion of wire. As the wire is thus severed, a pin 111 in the bracket 80 (Fig. 4) acts by engagement with the tail portion 90 to swing the pawl 88 in the direction to disconnect the slide 38 and the cutter slide 86. As the pawl 88 is thus operated, the block 96 acts by engagement with the roll 100 to swing the bell-crank lever 98 in the direction to move the cutter slide 86 rearwardly until the adjustable screw 95 carried by the slide 86 engages the head of the machine, thus retracting the cutter 84. In the continued forward movement of the slide 38 the block 96 passes under the roll 100.

The outside former 48 is carried by a slide 110 which is mounted in an inclined guideway formed in the forward end of the slide 38 (Fig. 2). Formed in the slide 110 is an elongated slot 112

(Fig. 5) in which there is slidably mounted a block 114 on which there is formed a trunnion 116 that extends through an elongated slot 118 in the slide 110 and into a block 120 (Fig. 2) 5 slidably mounted in a forwardly and rearwardly extending slot 122 formed in the forwardly extending arm of a bell-crank lever 124 which is fulcrumed at 126 to the slide 38. The block 114 is bored to receive a spring 128 (Fig. 5) that 10 bears at its lower end against the slide 110 and acts to hold the slide normally in engagement with the block 114 at the upper end of the elongated slot 112. The bell-crank lever 124 is provided with a rearwardly extending arm 130 15 carrying a roll 132 that extends into a cam path 134 formed in the bracket 56. The inside former 50 is slidably mounted in a guideway 135 formed in the forward end of the slide 38 (Fig. 6), the inside former being arranged for movement into 20 and out of operative relation to the outside former 48 and being normally held in its forward position by means of a torsion spring 136 (Fig. 3) that is coiled about the right-hand end portion of a short shaft 138 mounted to turn in the forward end of the slide 38. The shaft 138 has formed integrally with it a downwardly extending arm 140 (Fig. 6) the rounded lower end portion of which extends into a similarly shaped recess 141 in the inside former 50. Clamped to 25 the reduced right-hand end of the shaft 138 (Figs. 2 and 3) by means of a nut 142 is an arm 144 which, as shown in Fig. 2, is provided with a rearward projection 146 that acts by engagement with an adjustable screw 148 carried by 30 the slide 38 to limit and determine the forward position of the inside former 50. The arm 144 extends forwardly and upwardly as shown in Fig. 2 and lies in the path of movement of a roll 150 carried by a depending portion 152 on 35 the forwardly extending arm of the bell-crank lever 124.

It will be understood that the outside former 48 is provided with a passage 153 (Fig. 10) for the driver 40 in alignment with a similar driver passage 155 formed in the wiper or staple-guiding nozzle 36 and that the inside former 50 normally extends into position to cooperate with the outside former 48 and to act as a support for the fed-in portion of wire. The shape of the cam path 134 is preferably such that substantially at the beginning of the forward movement of the slide 38 the bell-crank lever 124 is swung in a counterclockwise direction (Fig. 2) to impart downward movement to the slide 110 through the block 114 and the spring 128 to cause the outside former 48 yieldingly to clamp the fed-in portion of wire against the inside former 50 during the wire-severing or cutting operation. The length of the slot 112 in the slide 110 is preferably such that the bell-crank lever 124 thereafter swings relatively to the slide 110 during the forward movement of the cutter 84 to sever the fed-in portion of wire, thus compressing the spring 128, after which the block 114 engages the slide 110 at the lower end of the slot 112. Thereafter, in response to continued counterclockwise swinging movement of the bell-crank lever 124, the outside former 48 is moved positively downward relatively to the inside former 50 to form a substantially U-shaped staple around the inside former, the outside former then continuing to move downwardly until its lower end face engages a shoulder 154 on the wiper or staple-guiding nozzle 36. At a predetermined time in the swinging movement of the bell-crank

lever 124 and preferably after the staple has been fully formed, the roll 150 acts by engagement with the arm 144 to rock the shaft 138 in the direction to operate the arm 140 to retract the inside former 50 against the resistance of its spring 136. It will be understood that with the outside former in its lowermost position there is provided a substantially continuous passage through it and through the wiper 36 for the staple and the driver 40 and that the staple and driver passage are moved into alignment with the driver 40 the position of which is determined by engagement of the abutment 44 on the slide 38 with the abutment 46 on the driver bar 42. At the end of the over-wiping operation, as previously explained, the driver 40 is released to the action of its operating spring for the insertion of a staple which is driven through the over-wiped margin of the upper and through the insole, the ends of its legs being clinched on the iron plate on the bottom of the last. The means for feeding the wire to form the staples may be and preferably is substantially the same as that fully shown and described in Letters Patent No. 1,731,853 granted October 15, 1929 upon an application of George Goddu and need not be described herein in detail. Briefly stated, the wire is led from a reel and idler (not shown) downwardly between feed wheels 158 and 160 (Fig. 3) and thence through a flexible tube 162 and a sleeve or quill 164 (Fig. 7) to the wire-guiding nozzle 74. The feed wheel 158 is operated by a ratchet and pawl mechanism 166 (Fig. 3) through an adjustable link 168 and a bell-crank lever 170 provided with a roll 172 (Figs. 1 and 3) engaged by a cam wheel 174 fast on a cam shaft 176 which is rotatably mounted in a bracket 178 secured to the head 26 of the machine by screws 180, one of which is shown in Fig. 3. The bell-crank lever 170 is pinned to a rock shaft 162 which is supported in bearings in the bracket 178, and coiled about the left-hand end-portion of the rock shaft 182 (Fig. 1) is a torsion spring 184 that tends to rock the shaft and to swing the bell-crank lever 170 in the direction to hold the roll 172 in engagement with a cam path 186 formed on the left-hand end face of the cam wheel 174 (Fig. 3). Fast on the cam shaft 176 is a bevel gear 188 that meshes with a smaller bevel gear 190 secured to the lower end of a vertical shaft 192 which is rotatably mounted in a bearing in the head 26 and at its upper end is geared to the main cam shaft 72 of the machine. The construction is such that the cam shaft 176 is rotated through 180° for one complete movement of rotation of the main cam shaft 72 in each cycle of operations of the machine, the cam 186 being so shaped that the bell-crank lever 170 is first swung in a clockwise direction (Fig. 3) by the action of the spring 184 on the rock shaft 182 substantially at the beginning of each cycle of operations of the machine and before the main slide 38 begins its forward movement, after which the bell-crank lever 170 is swung reversely by the cam 186 to its initial starting position. It will be understood that clockwise swinging movement of the bell-crank lever 170 will act through the ratchet and pawl device 166 to rotate the feed wheel 158 to feed a length of wire between the inside and outside formers of the machine.

In the machine herein shown there is provided an adjustable stop, illustrated as a screw 194, which acts by engagement with an arm 196 on the bell-crank lever 170 to limit the extent of clock-

wise swinging movement of the bell-crank lever (Fig. 3) under the influence of the spring 184, thus stopping the operation of the feed wheel 158 when a predetermined length of wire is fed into position to be acted upon by the inside and outside formers of the machine. It will be understood that by varying the position of the adjustable stop screw 194 the extent of clockwise swinging movement imparted to the bell-crank lever 170 may be varied as desired to vary the length of the wire fed to form a staple. As herein shown, the adjustable screw 194 is carried by a plunger 198 which is vertically movable in a recess in the bracket 178, a lock nut 200 being provided for holding the screw 194 in adjusted position relatively to the plunger. The plunger 198 rests on the peripheral edge face 202 of a segment 204 that is pinned to the left-hand end portion of a shaft 206 which is mounted in a bearing in the above-mentioned bracket 80. The peripheral edge face 202 of the segment 204 is eccentric to the axis of the shaft 206 (Fig. 1) and, in order that the segment may be rotated quickly to vary the heightwise position of the plunger 198 and the stop screw 194, and thus to vary the length of wire fed to form the staples and consequently the lengths of the staples, for operating upon different portions of the same shoe, there is fast to the right-hand end-portion of the shaft 206 a device comprising a hand lever 208 (Figs. 2 and 3). It will be understood that a finer adjustment of the length of wire fed may be made by adjustment of the screw 194 relatively to the plunger 198. For determining the proper limits of movement of the hand lever 208 in opposite directions to vary the position of the adjustable stop 194 and thereby to control the lengths of feed of the wire in accordance with the desired lengths of the staples to be formed in operating upon different portions of the same shoe, there are provided stops 214, 215 (Fig. 2) adjustably secured in a curved guideway 216 formed in a bracket member 218 which is secured to the bracket 80 by screws 219.

As previously pointed out, the stationary cutter or wire-guiding nozzle 74 (Figs. 3 and 10) is carried by a bracket 76 on which is slidably mounted the movable cutter 84. The bracket 76 is adjustable laterally of the slide 38 on the guideway 78 (Figs. 1 and 4) formed on the bracket 80 and pivotally connected to the bracket 80 is a lever 220 (Fig. 4) provided with an upwardly extending arm which is forked to straddle a pin 222 projecting from the bracket 76 and with a downwardly extending arm carrying a pin 224. The pin 224 is arranged to extend into a peripheral cam slot 226 formed in the segment 204. The shape of the cam slot 226 is such that, in all positions of adjustment of the segment 204 and the adjustable stop 194 to vary the length of wire fed to form the staples, the stationary and movable cutters 74 and 84 will be positioned in proper relation to the inside and outside formers of the machine to insure that the legs of each staple when formed from each severed piece of wire will be of substantially the same length.

In the use of the illustrated machine for last-ing shoes of the through-and-through sewed type, it is contemplated that staples will be formed of sufficient length to insure that the ends of their legs will penetrate entirely through the insole but only far enough to cause a slight clinching of the ends of the legs on the metal plate P (Fig. 15) on the bottom of the last in the driving operation, thus insuring against any danger of

injury to the foot of the wearer of the shoe such as might occur if excessively long staples improperly clinched were used. Since the upper materials at the toe and heel ends are of greater thickness than along the sides of the shank and ball portions of the shoe because of the added thickness of the toe stiffener around the toe end and the counter around the heel end, it will be necessary for the operator to vary the adjusted position of the stop 194 so that the desired lengths of staples will be formed for operating upon these different portions of the shoe. By adjustment of the stops 214 and 215 along the curved guideway 216 the lengths of the staples formed for use in operating upon different portions of the shoe may be varied and determined as desired.

In the illustrated construction, means is provided for swinging the device or hand lever 293 between the limits determined by the adjustable stops 214, 215 in response to the movements of the edge gage 23 into and out of operative position. As shown particularly in Fig. 2, there is pivotally connected to the edge gage 23 a rod 223 that extends rearwardly through a stud 230 which is pivotally connected to the device 208. Mounted on the rod 223 are adjustable collars 232, 234 that may be secured in adjusted position on the rod by set screws 233. The construction is such that as the edge gage 23 is moved forwardly to its operative position the collar 232 will act by engagement with the stud 230 to swing the device 208 in a counterclockwise direction (Fig. 2) from the position determined by the stop 214 into the position determined by the adjustable stop 215, and rearward movement of the edge gage 23 to its initial inoperative position would cause the adjustable collar 234 on the rod 223 to engage the stud 230 and to swing the device 208 reversely into the position determined by the adjustable stop 214. As previously mentioned, it will be understood that the stops 214 and 215 will be adjusted along the curved guideway 216 so as to vary the adjusted position of the stop screw 194 to control the lengths of feed of the wire in accordance with the desired lengths of the staples to be formed in operating upon the different portions of the shoe bottom. Since it is necessary for the operator to move the edge gage 23 forwardly to its operative position in lasting around the toe end of the shoe and at the opposite sides thereof in locations at or rearwardly of its heel breast line, and to move the edge gage to its rearward inoperative position in lasting along the sides of the shank and ball portions of the shoe, the means thus provided for controlling the lengths of fastening material fed to form the staples in response to the movements of the edge gage 23 not only avoid the necessity for the operator to make a separate adjustment of the stop 194 in operating upon each different portion of the shoe bottom but insure that a staple of the proper length will be formed and driven in each location. It will be understood that the collars 232 and 234 will be adjusted on the rod 223 in proper relation to the stud 230 so as to cause the device 208 to be swung between the limits determined by the stops 214 and 215 without limiting the movements of the edge gage 23 into and out of operative position.

In the illustrated machine, means is provided for rotating the wire from which the staples are formed about its longitudinal axis between successive wire-cutting operations in such manner as to cause the severing means to form oppositely beveled ends on the same side of each severed

piece of wire. As before stated, the wire W (Figs. 11 to 14 inclusive) is fed through a sleeve or quill 164 to the wire-guiding nozzle or cutter 74. The wire W as shown is preferably angular in cross-section and the quill 164 is provided with enlarged central recesses 235, 236 (Fig. 7) to receive the wire, the recess 236 terminating short of the outlet end of the quill which is slotted at 233 to permit the wire slidably to engage the quill. Formed on one end of the quill 164 is a U-shaped tongue 240 (Figs. 7 and 10) which is arranged to extend into a transverse slot 242 formed across one end of a bushing 264 that is rotatably mounted in the bracket 76. For holding the quill 164 against endwise movement in the bushing 264 there is provided a finger 246 which is fast to the outer end of a pin 248 adjustably mounted in the bracket 76, the finger being slotted at its upper end to straddle the flexible tube 162. A set screw 250 (Fig. 10) is provided in the nozzle 74 for holding the pin 248 against rotation with the finger 246 in engagement with the end face 252 of the quill 164. Formed on the bushing 264 is a bevel gear 254 that meshes with segment teeth 256 formed on a small bracket 258 which is secured to or formed integral with a short laterally extending shaft 260 supported by a bearing in the bracket 76 (Fig. 1). The bracket 258 is formed in two parts, as shown in Figs. 1 and 3, and these parts are adjustable relatively to each other about the axis of the shaft 260 and are held in adjusted position by means of a screw 262 that is threaded in one part of the bracket 258 and extends through an elongated slot 264 (Fig. 1) formed in the other part of the bracket. The bracket 258 has a laterally extending projection 266 provided with a slot 268 into which extends a roll 270 carried by one arm of a bell-crank lever 272 which is fulcrumed at 274 to the bracket 76 and is provided with a second arm 276 carrying a roll 278 arranged to extend into a cam path 280 (Figs. 3 and 8) formed in the side face of the cam wheel 174. As previously pointed out, the shaft 176 is geared to the main cam shaft 72 of the machine and receives a turning movement through 180° in each cycle of the machine in response to one complete movement of rotation of the shaft 72. The shape of the cam 280 is such that in each cycle of the machine, after a portion of wire has been fed into position between the inside and outside formers of the machine and prior to the forward movement of the slide 38, the lever 272 is swung about its pivot 274 in one direction to rotate the bracket 258 and, through the bevel gear 254, to cause the sleeve 244 and the quill 164 to rotate the wire through 90° about its longitudinal axis, and after the fed-in portion of wire is severed by the cutters 84 and 74 in the forward movement of the slide 38, the lever 272 is swung in a direction opposite to the direction of its first swinging movement to its initial starting position. As the lever 272 is thus swung reversely to its initial starting position, the sleeve 244 and the quill 164 are rotated through 90° in the direction opposite to the direction of their first movement of rotation, thus removing the twist from the wire and maintaining it in an untwisted condition for the next succeeding wire-feeding operation. It will be evident that as the wire is fed in the next cycle of the machine, the beveled end 282 (Fig. 11) of the wire will have been rotated through 90° about the longitudinal axis of the wire from the position in which the piece

was severed in the preceding cycle. The shape of the other half of the cam 280 is such that in this next cycle of operations of the machine, after the feeding operation and before the severing operation, the lever 272 is swung in a direction opposite to the direction of its first swinging movement in the last preceding cycle, so that the beveled end 282 of the wire will have been rotated through 180° about the longitudinal axis of the wire before the next piece is severed (Fig. 12). As the fed-in portion of wire is then severed in response to the forward movement of the slide 38, the angular faces on its opposite ends will be located on the same side of the wire. Thereafter, the cam 280 will swing the lever 272 reversely to its initial starting position, thus causing the wire to be rotated through 90° to remove the twist in the wire after the wire-severing operation. From the above description it will be evident that the wire W is turned 180° first in one direction between successive wire-cutting operations and then in the opposite direction before the next wire-cutting operation to cause the angular faces on the opposite ends of each severed piece of wire to be located in the desired relation, 90° of each turning movement occurring after each severing operation so that the wire is in untwisted condition each time it is fed. Accordingly, as the wire is fed it offers no resistance to the action of the feed rolls 158 and 160 nor is there any tendency for the wire to rotate the quill 164 and bushing 264 such as would occur if the wire were fed in a twisted condition. The feeding and turning movements imparted to the wire during two successive cycles of operation of the machine are illustrated diagrammatically in Figs. 11 to 14 inclusive. As shown particularly in Figs. 12 and 14, the passage 284 for the wire W in the nozzle 14 is angular in cross section and is sufficiently large to permit the wire to be turned therein, two surfaces of the passage acting by engagement with adjacent faces of the wire to support it during the wire-cutting operation.

In the illustrated machine each staple is formed with its cross-bar extending laterally of the slide 38 so that as a shoe is presented by the operator in different positions in engagement with the bottom rest 20 and with either the edge gage 22 or the edge gage 28 in the progressive lasting of its opposite sides and around the toe end a staple will be driven in each location with its cross-bar extending substantially parallel to the edge of the shoe bottom. Fig. 15 shows a section of a shoe of the through-and-through sewed type illustrating the relation of the staples S to the seam t whereby the outsole is secured to the insole. It will be evident that the staples are driven, in the locations illustrated, each with the ends of its legs deflected substantially in the plane of the cross-bar of the staple so as to avoid any danger that they will interfere with the outsole stitches.

Having described the invention, what I claim as new and desire to secure by Letters Patent of the United States is:

1. In a cyclically operating fastening-inserting machine, means for feeding fastening material, means for severing from said material a piece to form a fastening by a cut extending at an oblique angle to the longitudinal axis of the material after the feeding of the material, and means for turning said fastening material about its longitudinal axis prior to the severing operation through an angle of 90° in one direction in one cycle of operations of the machine and

5 through the same angle in the opposite direction in the next cycle of operations, said turning means being so constructed as to turn the material reversely to its starting position in each cycle after the severing operation.

2. In a cyclically operating fastening-inserting machine, means for severing a piece from fastening material by a cut extending at an oblique angle to its longitudinal axis, and means for feeding the fastening material to said severing means and for turning the material about its longitudinal axis, first in one direction before the severing operation and then in the opposite direction after the severing operation to present the fastening material in an untwisted condition for the next feeding operation, said means being constructed to reverse the direction of both said turning movements in alternate cycles of operations of the machine to cause the severing means to form opposite bevels on the same side of each severed piece at the ends of said piece.

3. In a cyclically operating fastening-inserting machine, means for severing a piece from fastening material by a cut extending at an oblique angle to its longitudinal axis, means for feeding the fastening material to said severing means, and means for turning said fastening material about its longitudinal axis after it has been thus fed, first in one direction prior to the severing operation and then in the opposite direction after the severing operation to present the material in an untwisted condition for the next feeding operation, said last-named means being constructed to reverse the direction of both said turning movements in alternate cycles of operations of the machine to cause the severing means to form oppositely inclined faces on the ends of each severed piece at the same side of the piece.

4. In a cyclically operating fastening-inserting machine, the combination with staple-forming means and means for feeding fastening material into position to be acted upon by said staple-forming means, of means for severing each fed-in portion of fastening material by a cut extending at an oblique angle to its longitudinal axis, and means for turning said fastening material after it has been thus fed, first in one direction prior to the severing operation and then in the opposite direction after the severing operation to present the material in an untwisted condition for the next succeeding feeding operation, said turning means being constructed to reverse the direction of both said turning movements in alternate cycles of operations of the machine to cause the inclined faces formed by the severing operation to be located on the same side of each severed piece of material.

5. In a cyclically operating fastening-inserting machine, means for severing a piece from fastening material by a cut extending at an oblique angle to its longitudinal axis, means for feeding the fastening material to said severing means, a member for guiding the fastening material to said severing means, and means for rotating said guiding member first in one direction after each feeding operation and prior to each severing operation and then in the opposite direction after each severing operation to present the fastening material in an untwisted condition for the next feeding operation, said last-named means being constructed to reverse the direction of rotation of said guiding member in alternate cycles of operations of the machine before the severing operation to cause the severing means to

form bevels on the same side of each severed piece at the ends of the piece.

6. In a cyclically operating fastening-inserting machine, means for severing a piece from fastening material by a cut extending at an oblique angle to its longitudinal axis, means for feeding the fastening material to said severing means, and means for turning the fastening material 90° about its longitudinal axis after it has been thus fed but prior to the severing operation and for thereafter turning it reversely 90° to remove the twist from the material for the next succeeding feeding operation, said last-named means being constructed to reverse the direction of both said turning movements in alternate cycles of operations of the machine to cause the fastening material to be turned alternately in opposite directions 180° about its longitudinal axis between successive severing operations, whereby the bevels on the opposite ends of each severed piece will be located on the same side of the piece.

7. In a cyclically operating fastening-inserting machine, means for feeding fastening material, means for severing a piece from said fastening material by a cut extending at an oblique angle to its longitudinal axis, and means for rotating the fastening material alternately in opposite directions 180° about its longitudinal axis relatively to the severing means between successive severing operations to cause the inclined faces on the opposite ends of each severed piece to be located on the same side of the piece.

8. In a cyclically operating fastening-inserting machine, wire-feeding means, wire-cutting means comprising a pair of relatively movable cutters arranged to cut the wire at an oblique angle to its longitudinal axis to provide a piece to form a fastening, a member for guiding the wire from said feeding means to said cutting means, and cam-controlled means for rotating said guiding member first in one direction after each feeding operation and prior to each cutting operation to cause the wire to be turned 90° about its longitudinal axis and for thereafter rotating the guiding member to the same extent in the opposite direction after each cutting operation, said cam-controlled means being constructed to reverse the direction in which the guiding member is rotated prior to the cutting operation in alternate cycles of operations of the machine to cause the wire to be turned alternately in opposite directions 180° about its longitudinal axis between successive cutting operations but to be presented in an untwisted condition for each operation of the wire-feeding means.

9. In a fastening-inserting machine, fastening-inserting mechanism movable relatively to a shoe to insert fastenings to fasten the upper to a sole, means for severing from fastening material pieces of different lengths and for forming each severed piece into a fastening, means for feeding fastening material to said severing and forming means, a lever swingable relatively to the feeding means to operate said feeding means, an adjustable stop for limiting the movement of said lever to determine the length of fastening material fed to form a fastening, a gage adjustable into and out of a single, predetermined operative position to serve as a support for the shoe in operating upon some portions only of the shoe bottom, and a member common to said stop and gage for adjusting them simultaneously.

10. In a fastening-inserting machine, fastening-inserting mechanism movable relatively to a shoe to insert fastenings to fasten the upper to a

sole, means for severing from fastening material pieces of different lengths and for forming each severed piece into a fastening, means for feeding fastening material to said severing and forming means, a member separate from the feeding means and movable relatively thereto for operating said feeding means, a stop for limiting the movement of said member to determine the length of fastening material fed to form a fastening, a gage movable forwardly and rearwardly into and out of predetermined positions to serve as a support for the shoe in operating upon some portions of the shoe bottom, and means operative in response to the forward and rearward movements of said gage for varying the position of said stop to vary the length of the fastening material fed.

11. In a fastening-inserting machine having fastening-forming means and driving means movable inwardly over the bottom of a shoe into position to fasten the upper to a sole, a shoe bottom rest, a pair of relatively movable edge gages arranged for alternative use respectively to position the shoe in operating along different portions of the shoe bottom, means for feeding fastening material to said forming means, means for severing from said fastening material pieces of different lengths, a member separate from the feeding means movable yieldingly relatively thereto to operate said feeding means, a spring for moving said member, a stop for limiting the extent of yielding movement imparted to said member by said spring to determine the length of fastening material fed to form a fastening, and means controlled by the relative movement of said edge gages for varying the position of said stop to vary the length of the fastening material fed.

12. In a fastening-inserting machine, fastening-forming and driving mechanism movable relatively to a shoe to fasten the shoe upper to a sole, means for feeding fastening material to said forming and driving mechanism, means for severing from the fastening material pieces of different lengths, a separate member swingable relatively to the feeding means to operate said feeding means, a stop for limiting the extent of swinging movement of said member to determine the length of the fastening material fed, said stop being adjustable in a heightwise direction only, a pair of edge gages arranged for use alternatively to support the shoe in operating upon different portions of the shoe bottom, one of said gages being fixed and the other being movable, and means controlled by said movable gage for varying the heightwise position of said stop to vary the length of the fastening material fed.

13. In a fastening-inserting machine, fastening-forming means and driving means movable relatively to a shoe to fasten the upper to a sole, a pair of edge gages arranged for alternative use respectively to position the shoe in operating along different portions of the shoe bottom, one of said gages being fixed and the other being movable forwardly and rearwardly relatively to the fixed gage into and out of a predetermined operative position for use, means for feeding fastening material to said forming means, means for severing from the fastening material pieces of different lengths, a member movable relatively to the feeding means for operating said feeding means, means for moving said member yieldingly, a stop for limiting the extent of yielding movement of said member to

determine the length of fastening material fed to form a fastening, a slide adjustable to vary the position of said severing means relatively to said forming means, and means controlled by the forward and rearward movements of said movable edge gage for varying the position of said stop and for simultaneously adjusting said slide to vary the length of the fastening.

14. In a fastening-inserting machine having fastening-forming means and driving means movable relatively to a shoe to fasten the upper to a sole, a fixed edge gage and a movable edge gage arranged for alternative use respectively to position the shoe in operating along different portions of the shoe bottom, means for feeding fastening material to said forming means, means for severing from the fastening material pieces of different lengths, a lever separate from the feeding means swingable to operate said means, said lever swinging yieldingly when operating, a stop for limiting the extent of the yielding swinging movement of said lever to determine the length of the fastening material fed to form a fastening, a segmental member mounted for turning movement and having an eccentric surface thereon to engage said stop and vary the position thereof, thereby varying the length of the fastening material fed, a device for turning said segmental member, adjustable stops for predetermined different limits of movement of said device in opposite directions, and means for moving said device between the limits determined by said stops in response to the movements of said movable edge gage into and out of position for use.

15. In a fastening-inserting machine, means for forming fastenings, means for feeding fastening material to said forming means, means for severing from the fastening material pieces of different lengths, a separate member movable relatively to the feeding means to operate said feeding means, means for moving said member yieldingly when operating a stop for limiting the extent of yielding movement of said member to determine the length of fastening material fed, a device mounted for rotary movement to vary the position of said stop and having means thereon simultaneously to effect a relative adjustment of said severing means and the forming means to vary the length of the fastening, and means for predetermined different positions of said device.

16. In a fastening-inserting machine, means for forming fastenings, means for feeding fastening material to said forming means, means for severing from the fastening material pieces of different lengths, a member movable relatively to the feeding means to operate said feeding means, a spring for moving said member yieldingly, a stop for limiting the extent of yielding movement of said member to determine the length of fastening material fed, said stop being adjustable in a vertical direction, a slide adjustable to vary the lateral position of said severing means relatively to said forming means, and means for varying the vertical position of said stop and for simultaneously adjusting said slide laterally to vary the length of the fastening.

17. In a fastening-inserting machine, means for forming fastenings, means for feeding fastening material to said forming means, means for severing from the fastening material pieces of different lengths, a member separate from the feeding means and movable relatively thereto to operate said feeding means, a vertical stop for

limiting the extent of movement of said member to determine the length of fastening material fed, a slide adjustable to vary the lateral position of the severing means relatively to said forming means, a segmental member mounted for turning movement to vary the heightwise position of said stop and simultaneously to adjust said slide laterally to vary the length of the fastening, a device for turning said segmental member, and means for predetermined different limits of movement of said device in opposite directions.

18. In a fastening-inserting machine, means for forming fastenings, means for feeding fastening material to said forming means, means for severing from the fastening material pieces of different lengths, a member separate from the feeding means and movable relatively thereto to operate said feeding means, a spring for operating said member yieldingly, a stop for limiting the yielding movement of said member to determine the length of the fastening material fed to form a fastening, said stop being adjustable in a vertical direction only, means for varying the vertical position of said stop and for simultaneously adjusting said severing means relatively to said forming means to vary the length of the fastening, said means including a segmental rotary member, and means for rotating said segmental member between two predetermined positions.

19. In a fastening-inserting machine, staple-forming means, means for feeding fastening material to said forming means, means for severing from the fastening material pieces of different lengths, a member movable to operate said feeding means, a stop for limiting the movement of said member to determine the length of fastening material fed, and a device for varying the position of said stop to vary the length of fastening material fed and for simultaneously adjusting the severing means relatively to the forming means so as to cause the legs of each staple when formed to be of equal lengths, said device comprising a member having a surface thereon engaging said stop and having a cam slot formed therein for causing the adjustment of said severing means.

20. In a fastening-inserting machine, staple-forming means, means for feeding fastening material to said forming means, means for severing from the fastening material pieces of different lengths, a lever swingable relatively to the feeding means to operate said feeding means, said lever swinging yieldingly during its operative stroke, a stop for limiting the extent of yielding swinging movement of said lever to determine the length of fastening material fed, a slide adjustable to vary the position of said severing means relatively to said forming means laterally of the machine, a rotatable member having an eccentric surface thereon for engaging said stop to vary its position and thus to vary the length of the fastening material fed, and connections between said rotatable member and the slide for adjusting the slide laterally to vary the position of the severing means relatively to said forming means so as to cause the staple when formed from the severed length of fastening material to have legs of the same length, said connections including a lever operated by rotation of said rotatable member.

21. In a fastening-inserting machine, means for severing from fastening material pieces of different lengths and for forming each severed piece into a fastening, means for feeding fas-

tening material to said severing and forming means, a cam-controlled spring-operated lever separate from the feeding means for operating said feeding means, said lever operating yieldingly during its operative movement, a stop for limiting the yielding operative movement of said lever to determine the length of fastening material fed to form a fastening, a segmental member mounted for turning movement relatively to the stop and having an eccentric surface thereon for engaging the stop to vary the position of said stop, thereby varying the length of the fastening material fed, a device for turning said member, and means for predetermining different positions of said device.

22. In a fastening-inserting machine, means for severing from fastening material pieces of different lengths and for forming each severed piece into a fastening to be inserted into a work

piece, rotary means for feeding fastening material to said severing and forming means, a pivoted member movable relatively to the rotary feeding means about a fixed pivot to operate said feeding means, a stop movable heightwise for limiting the extent of pivotal movement of said member to determine the length of fastening material fed by said feeding means to form a fastening, a rotatable eccentric for varying the heightwise position of said stop and for thereby varying the length of fastening material fed, a device for rotating said eccentric, means for variably limiting movement of said device, and means connected to said device and movable into and out of operative position by the movement thereof for positioning the work piece relatively to said severing and forming means.

BENJAMIN B. BLANCHARD.
